FIG1

FIG2

FIG3

FIG4

FIG. 1 is a front elevational view of a hand-operated sparking spin wheel toy;

FIG. 2 is a view of one side thereof, on an enlarged scale, taken along line 2—2 of FIG. 1 and showing my new design;

FIG. 3 is a view of the opposite side thereof showing my new design, the view being taken on line 3—3 of FIG. 1; and

FIG. 4 is a cross-sectional view taken substantially along line 4—4 of FIG. 2.

The spinning cord has been omitted from FIGS. 2 through 4 for convenience of illustration.

I claim:

The ornamental design for a hand-operated sparking spin wheel toy, substantially as shown and described.
